US00D984894S

(12) **United States Design Patent** (10) **Patent No.:** **US D984,894 S**
(45) **Date of Patent:** ** *May 2, 2023

(54) **DRINK CUP LID**

(71) Applicant: **Berry Global, Inc.**, Evansville, IN (US)

(72) Inventor: **Jonathan Eickhoff**, Evansville, IN (US)

(73) Assignee: **Berry Global, Inc.**, Evansville, IN (US)

(*) Notice: This patent is subject to a terminal disclaimer.

(**) Term: **15 Years**

(21) Appl. No.: **29/765,808**

(22) Filed: **Jan. 12, 2021**

Related U.S. Application Data

(62) Division of application No. 29/682,409, filed on Mar. 5, 2019, now Pat. No. Des. 911,168.

(51) **LOC (14) Cl.** **09-07**

(52) **U.S. Cl.** **D9/434**

(58) **Field of Classification Search**

(57) **CLAIM**

The ornamental design for a drink cup lid, as shown and described.

DESCRIPTION

FIG. 1 is a top perspective view of a drink cup lid showing my new design;

FIG. 2 is a bottom perspective view thereof;

FIG. 3 is a top plan view thereof; and,

FIG. 4 is a bottom view thereof.

In the drawings, the broken lines show portions of a drink cup lid and form no part of the claim.
